CLAIM

We claim the ornamental design for a crawler track shoe, as shown and described.

DESCRIPTION

FIG. 1 is a perspective view of a crawler track shoe according to one construction.

FIG. 2 is a perspective, top, right side view of the crawler track shoe of FIG. 1.

FIG. 3 is a top view of the crawler track shoe of FIG. 1.

FIG. 4 is a bottom view of the crawler track shoe of FIG. 1.

FIG. 5 is a left side view of the crawler track shoe of FIG. 1.

FIG. 6 is a right side view of the crawler track shoe of FIG. 1.

FIG. 7 is a rear view of the crawler track shoe of FIG. 1; and,

FIG. 8 is a front view of the crawler track shoe of FIG. 1.

The elements shown in broken lines are included for the purpose of illustrating environment and form no part of the claimed design.
